UNITED STATES PATENT OFFICE.

FITZ WILLIAM SARGENT, OF MAHWAH, NEW JERSEY, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,158,561.

Specification of Letters Patent.

Patented Nov. 2, 1915.

Application filed August 20, 1915. Serial No. 46,462.

To all whom it may concern:

Be it known that I, FITZ W. SARGENT, a citizen of the United States, and a resident of Mahwah, in the county of Bergen and State of New Jersey, have made and invented certain new and useful Improvements in Brake-Shoes, of which the following is a specification.

This invention relates to brake shoes, and concerns in particular that class or type which are provided with reinforcing backs, it being among the objects of the present invention to so construct or form the shoe as to obtain the most secure and permanent anchorage of the body of the shoe to the reinforcing back, so that as the body of the shoe becomes excessively worn and cracked, the metal will not fall away or become separated from the reinforcing back, either in whole or in part.

It has been found in practice that in brake shoes, as ordinarily constructed, the expanded metal, which is contained in the body of the shoe and holds the same together should it become cracked, does not prevent the breaking up or separation of that portion of the body of the shoe which is anchored to the back thereof after the greater or larger part of the body and the expanded metal inserts have been worn away. Ordinarily this unreinforced portion of the body metal of the worn shoe becomes cracked and broken in service and separates and falls away from the reinforcing back.

In order to avoid the foregoing disadvantages, I provide a binding and reinforcing member, preferably formed of expanded or open-work metal, and securely attach the same to the steel reinforcing back, so that it contacts with the same throughout its entire area. The cast metal of the body of the shoe is thus reinforced at its connection and securement to the reinforcing back, and the reinforcing back and expanded metal act as a single unit for the reinforcement and anchorage of the body of the shoe. Thus, the metal which is anchored to the back, as well as adjacent portions thereof, is reinforced throughout, and all danger and likelihood of the body becoming fractured and broken between the expanded metal and the steel back, and the separation of the two, is eliminated.

Other objects and advantages will appear as the description proceeds, wherein it is to

be understood that changes in the precise embodiment of my invention can be made within the scope of what is claimed without departing from the spirit thereof.

The preferred embodiment of my invention is disclosed in the accompanying drawings, wherein:

Figure 1 is a view in side elevation and partially in section of a brake shoe embodying the characteristic features of my invention; Fig. 2 is a view in top plan of the brake shoe, portions thereof being broken away; Fig. 3 is a view in section taken on the line 3-3 of Fig. 1; Fig. 4 is a view in perspective of the reinforcing back and the binding member, illustrating the manner in which the two are wired and securely held together, resulting in their contact throughout.

Referring specifically to the several views, the reinforcing back 5 is provided with the looped portion 6, which, in conjunction with the openings 7, which extend through the sides thereof, form an integral key lug. The reinforcing back is further provided with the usual openings 8, into which the metal of the cast body of the shoe extends.

In order that the full benefit of the reinforcing back 5 will be realized and obtained, I provide a binding or reinforcing member 9 of a length and width approximating the over-all dimensions of a finished shoe, and preferably formed of open-work or expanded metal, and securely hold the same in contact with the reinforcing back by the wire loops 10, or analogous means. The binding and reinforcing member is curved so as to correspond to the back 5, and contacts with the same throughout the entire length thereof. In forming the shoe, the reinforcing back, with the binding member secured thereto, is placed within a mold, and the body 11 is cast thereto, portions of the metal flowing up and about the integral lug 6, and portions above the ends of the reinforcing back to form the end stops 12.

The metal which engages and becomes anchored to the reinforcing back is, accordingly, bound together and reinforced throughout by the expanded metal 9, with the result that this portion of the body of the shoe is materially strengthened, and is prevented from becoming fractured. The wearing body of the shoe may be provided, in addition to the reinforcing member above-

- outlined, with the ordinary form of body reinforcement such as a bundle of expanded metal, or the usual type of inserts, it being noted that there will be no likelihood of the body of the shoe becoming fractured immediately adjacent the reinforcing back, as has heretofore been the case, sometimes resulting in the separation of the body of the shoe as a whole from the reinforcing back.
- 10 The secure anchorage of the binding member 9, within the cast body of the shoe, and its position beneath and across the looped lug, provide for the support and anchorage of the body metal of the shoe, even though the same should become cracked between the sides of the lug. The binding member being approximately equal in width to that of the cast body of the shoe in which it is embedded, reinforces the same throughout. The expanded metal of the binding member in conjunction with the cast metal of the body is not in any way injurious to a car wheel, so that the shoe may be worn down to the steel back, with a minimum weight of scrap resulting.
- What I claim is:—
1. A brake shoe comprising a reinforcing back, a reinforcing and binding member of openwork metal contacting throughout with said back and a wearing body anchored to said back and reinforcing member.
2. A brake shoe comprising a reinforcing back, with a looped lug, a reinforcing member of open-work metal extending across the open portion of said lug and a wearing body anchored to said back and said reinforcing member.
3. A brake shoe comprising a reinforcing back with an integral open lug, a reinforcing and binding member contacting with said back and extending across the open portion of said lug, and a wearing body cast to said reinforcing member and said back.
4. A brake shoe comprising a reinforcing back with an open integral looped lug, a reinforcing member of open-work metal tied to and in contact throughout with said back, and a wearing body cast to said reinforcing member and said back.
5. A brake shoe comprising a back, a binding and reinforcing member of expanded metal contacting with said back and approximating the over-all dimensions of said shoe and a wearing body cast to said back and binding member.

Signed at Mahwah, in the county of Bergen and State of New Jersey this 18th day of August A. D. 1915.

FITZ WILLIAM SARGENT.
